FIG. 1

The characteristic feature of my design resides in the midsection gunwales, terminating short of the fore and aft portions of the hull, as shown.

I claim:

The ornamental design for a pirogue, as shown and described.
